UNITED STATES PATENT OFFICE.

THOMAS J. WALTON, OF CORSICANA, TEXAS.

GRATE.

SPECIFICATION forming part of Letters Patent No. 703,865, dated July 1, 1902.

Application filed January 29, 1902. Serial No. 91,796. (No model.)

To all whom it may concern:

Be it known that I, THOMAS J. WALTON, a citizen of the United States, residing at Corsicana, in the county of Navarro and State of 5 Texas, have invented new and useful Improvements in Grates, of which the following is a specification.

This invention relates to grates; and the object of the invention is to provide a simple 10 and efficient device of this character which can be produced at a low figure.

The grate is of inverted conical form and is supported for rotary movement by a perpendicular spindle or stem and is sustained in part 15 by a collar on said spindle or stem. The upper end of the latter has a succession of weakened portions, so that said stem or spindle can be shortened in order to lower the grate, and for this purpose the collar mentioned is 20 vertically adjustable, it being held in a desired position by a set-screw. The top or apex of the grate has a squared portion which may be embraced by a poker or like 25 part for the purpose of oscillating the grate and which is surmounted by a shoulder which may be engaged by said poker or like part to lift the grate.

The grate and its coöperating parts may be made of any suitable material, preferably of 30 cast-iron, and certain of the parts may, if desired, be formed integral.

Other objects and advantages will appear in the following description, while the novelty of the invention will be set forth in the 35 claims succeeding said description, and said invention is clearly illustrated in the accompanying drawings, forming a part of this specification, and in which—

Figure 1 is a side elevation of a grate including my improvements. Fig. 2 is an under side view of the grate proper detached. Fig. 3 is a detail perspective view of the base and spindle with the collar on the latter. Fig. 4 is a cross-section of the crown-piece of 45 the grate. Fig. 5 is a detail view of a poker. Fig. 6 is a plan view of a modified form of base.

The invention is not limited to the construction illustrated in detail and hereinafter described, for many changes may be made within the scope of my claims, and the grate, as will be evident, may be used with facility

in connection with different kinds of stoves. Said grate includes in its construction a base 55 10, which is shown as consisting of a plate or disk adapted to rest upon the bottom of a fire box or chamber. The base-plate 10 is shown as having a circular series of perforations or holes 11, through which bolts (not shown) can be passed to connect the plate to a stove or analogous apparatus.

The grate hereinafter described is supported for rotation and held from toppling over by the vertical spindle or stem 12, the lower end of which fits in a central opening 65 in the base-plate, and said shaft is held against rotation by a key 13, introduced in keyways or channels formed in the respective parts.

The grate is denoted in a general way by 70 14, and it will be seen that it is of inverted conical form, it being of skeleton construction, as will hereinafter appear.

The body of the grate is designated by 15, and it consists of a central hub perforated 75 for the reception of the spindle 12 and a plurality of radial arms 15', projecting from said hub. Diagonal ribs 16 are connected to the outer ends of said radial arms, and although the arms and ribs are shown as being in one 80 piece, this is not necessary, for they could very well be formed separately and bolted together. The ribs or arms 16 incline upward and inward and are united to the crown-piece 17, and they also extend below the body 15. The 85 crown-piece has on its under side and centrally thereof a seat or socket 18, into which the upper end of the spindle 12 is introduced, so that the grate turns upon the spindle, and in order to take the strain off the upper 90 end of the spindle which is weakened, as will hereinafter appear, the body of the grate is sustained by a collar 19 on said spindle and vertically adjustable and held in a desired 95 position by a set-screw carried thereby and adapted to engage the spindle. There are four of the diagonal ribs 16, and they converge toward the top of the grate and are embraced by rings 20, horizontally disposed and arranged in superposed order, they being separated a distance sufficient to permit the free 100 passage of a draft and the discharge of the ashes, but not far enough to cause the discharge of the fresh or partly-consumed fuel.

The rings are of progressively-decreasing diameter toward the top, and their outsides are rounded, which I may secure by making them circular in cross-section, as shown, or 5 half-circular in cross-section, or they may be of other shape, as may be desired. The rings 20 are shown as being integral with the ribs or arms 16; but this of course is not essential, for they can be made separately and suitably o connected together.

The upper end of the spindle 12 has a series of superposed annular grooves 21, which are of some depth, thereby producing a weakened portion the sections of which can be 5 broken off, one or more, to adjust the grate if, for example, the spindle is too high, and when the spindle is so shortened it will be of course necessary to correspondingly lower the collar 19. The rings 20 are of progressively-reduced sizes, so that by removing any one or more of them, commencing at the bottom and severing the corresponding portions of the ribs 16, the diameter of the grate at its base o can be decreased.

5 The crown-piece 17 has on its top a square shoulder 22, surmounted by the squared vertical extension 23, terminating in a shoulder 24, also square. The squared extension 23 can be straddled or gripped by the forked end 25 of the poker 26 for the purpose of rotating the grate, or by forcing the poker against the shoulder 24 the grate can be lifted. The crown-piece has exteriorly thereof several holes 27, (four being shown,) into one of which 5 the pointed end of an ordinary poker can be inserted to lift the grate, it being understood that independent means are provided for securing this function.

A grate constructed as hereinbefore described is economical, as by reason of its form it serves to shift and distribute the fuel from the center of fire-box to outer surface thereof, thereby securing a high degree of heat, and I obtain, also, advantageous ventilation 5 by the superposed rings. By raising the grate the contents of the fire-box can be readily discharged into the ash-box, and by rotating the grate in one of the ways set forth it can be properly cleared of ashes. Said o grate is also adjustable with respect to height and diameter and can be used effectively with different kinds of stoves.

In Fig. 6 I have shown a modified form of base, to which the spindle 12 is connected. 5 The base shown in said Fig. 6 consists of a hub or body 30, having a series of radial arms 31, four of which are shown, although this number may be varied, the arms having holes 32 at their outer ends or tips to receive bolts, o by which said base can be secured to a stove. The hub of course has a central hole to receive the spindle 12, which may be keyed or otherwise held in place. Although the modified form of base is shown as consisting of one

piece, this is not necessary, for it may be 65 composed of two or more parts and may be made from any suitable material, such as iron.

Having described the invention, what I claim is—

1. A grate having a body, ribs connected to 70 the body and converging toward the top of the grate, a crown-piece connected with the upper ends of the ribs and rings surrounding the ribs and located in superposed order and being of progressively-decreasing diameter 75 from the bottom toward the top, combined with a spindle for rotatively supporting said grate.

2. A grate having a body, ribs connected to 80 the body and converging toward the top of the grate a crown-piece connected with the upper ends of the ribs and rings surrounding the ribs and located in superposed order and being of progressively-decreasing diameter 85 from the bottom toward the top, combined with a spindle for rotatively supporting said grate, and a base-piece having a perforation to receive the spindle and the latter being keyed in place.

3. A grate having a body, ribs connected to 90 the body and converging toward the top of the grate, a crown-piece connected with the upper ends of the ribs, rings surrounding the ribs and located in superposed order and being of progressively - decreasing diameters 95 from the bottom toward the top, and a squared extension upon the crown-piece for receiving a poker.

4. A grate having a body, ribs connected to 100 the body and converging toward the top of the grate a crown-piece connected with the upper ends of the ribs, rings surrounding the ribs and located in superposed order and being of progressively - decreasing diameters 105 from the bottom toward the top, and a squared extension upon the crown-piece for receiving a poker and its upper end being shouldered and the crown-piece having holes for the insertion of a poker.

5. A spindle having weakened portions at 110 its upper end combined with a grate having a socket to receive said upper end, and means adjustably carried by the spindle to support the grate.

6. A base-piece having a vertical spindle 115 provided with deep annular grooves at its upper end combined with a grate having a socket to receive said upper end, and a collar adjustable on the spindle for supporting the grate. 120

In testimony whereof I have hereunto set my hand in presence of two subscribing witnesses.

THOMAS J. WALTON.
